UNITED STATES PATENT OFFICE.

WILLIAM F. LOTZ AND JOHN LEMON, OF LONDON, ENGLAND, ASSIGNORS
TO GEORGE W. MCGILL, OF NEW YORK, N. Y.

LAMP-BURNER.

SPECIFICATION forming part of Letters Patent No. 232,992, dated October 5, 1880.

Application filed August 10, 1880. (Model.)

To all whom it may concern:

Be it known that we, WILLIAM F. LOTZ and JOHN LEMON, of the city of London, in the county of Middlesex, England, have jointly 5 invented a new and useful Improvement in Lamp-Burners; and we do hereby declare the following to be a full and exact description thereof, reference being had to the accompanying drawings, making part of this specification, and to the figures and letters of reference marked thereon, in which similar letters of reference indicate corresponding parts.

This invention relates to a device for extinguishing a lamp by simply turning a key. 15 It consists in a sliding tube surrounding the wick-tube, which is moved up and down upon the wick-tube by means of a lever-key, and having at its upper end a hinged wing operated by a spring which automatically closes 20 down over the wick when said sliding tube is raised and automatically opens when said tube is depressed.

In the accompanying drawings we have shown our invention applied, first, to a lamp 25 with double wick-tubes, and, second, to a lamp with a single wick-tube.

Figure 1 is an elevation of the burner of a lamp with duplex wick-tube, which is above a 30 oil-cup and below the deflecting-dome. Fig. 2 is a vertical section of same in line *y y* of Fig. 3. Fig. 3 is a vertical section in line *x x* of Fig. 2. Fig. 4 shows a modification to adapt our invention to a lamp with a single wick-tube.

Like letters indicate the same parts in all the figures.

We will first give a detailed description of our invention as applied to a lamp with duplex wick-tubes.

40 A is the base of the burner, which is perforated in the usual manner. B B are the wick-tubes. C C are the sliding extinguishing-tubes, and c c are the extinguishing-wings hinged thereto. D is a shaft for operating the 45 extinguishing-tubes. d is a curved lever rigidly attached to said shaft, and d' is a key on the end of said shaft for operating the same. E is a connecting-block between the sliding tubes C C, and rigidly attached to both. E' is 50 a slotted stud or stirrup depending from said

block E, through which the curved lever *d* passes, and *e* is a cylindrical stud screwed into the upper side of said connecting-block E, and this stud *e* passes loosely through a horizontal plate, *e'*, extending across between the 55 sliding tubes, but not attached to either, so that it has a vertical movement between and independently of them. Between the block E and the plate *e'*, and surrounding the stud *e*, is a spiral spring, *f*.

The extinguishing-wings *c c* are bent inward at their bases below the pivots on which they turn, as shown at *c'* in Figs. 2 and 4, and said inwardly-projecting bases bear upon the horizontal plate *e'*. Said inwardly-projecting bases 65 may be formed by bending or striking up the lower ends of the wings *c c* or by soldering thereto strips of metal, as shown in the drawings.

From the shaft D a lever, *d''*, Fig. 2, projects laterally, to which a string, *d'''*, may be attached for operating the extinguisher when the lamp is in an elevated position.

The operation is as follows: When the lamp is burning the sliding tubes C C are depressed, 75 as shown in Fig. 1. To extinguish the flame the shaft D is turned in the direction to elevate the curved lever *d*, which carries up the block E, and with it the sliding tubes to which it is attached. When the horizontal plate *e'* 80 rises nearly to the top of the wick-tubes the spiral spring, acting upon said plate *e'*, forces it upward against the inwardly-projecting bases of the wings *c c*, and causes them to close suddenly over the wick-tubes, as shown 85 in Figs. 2 and 4, and extinguish the flame. When it is desired to relight the lamp the shaft D is turned in the direction to depress the curved lever *d*, which carries down the block E and the sliding tubes C C, causing the 90 wings *c c* to assume a vertical position, as shown in Fig. 1.

To adapt our invention to a lamp with a single wick-tube slight modifications are made, as shown in Fig. 4. In this case a plate, *E''*, 95 extending horizontally from the sliding tube C and rigidly attached thereto, performs the function of the connecting-block E, (shown in the other figures,) and the L-shaped plate *e''* performs the function of the plate *e'* (shown 100

in said other figures.) The vertical leg of said plate e'' passes through a slot in the plate E'' , which secures to it a correct vertical movement.

5 We do not limit ourselves to the use of the rock-shaft D , curved lever d , and stirrup E' to elevate and depress the sliding extinguishing-tubes, as other well-known equivalent devices for similar purposes—as, for instance, a rack and pinion—may be substituted without changing the principle of our invention.

What we claim as our invention is—

1. In combination with duplex wick-tubes, the sliding tubes C C , with the extinguishing-wings c c hinged thereto, the sliding block E , with stirrup E' , vertical stud e , horizontal plate s , spring f , shaft D , and curved lever d , all

constructed, combined, and arranged to operate substantially as shown and described.

2. In combination with a single wick-tube, ²⁰ the sliding tube C , with extension-plate E'' attached thereto and extinguishing-wing c hinged thereto, plate e'' , stirrup E' , vertical stud e , spring f , shaft D , and curved lever d , all constructed, combined, and arranged to ²⁵ operate substantially as set forth.

In testimony that we claim the foregoing as our invention we have hereunto affixed our signatures in the presence of two witnesses.

WILLIAM FREDERICK LOTZ.
JOHN LEMON.
